Atlys

UNITED STATES PATENT OFFICE.

HARRY MINTZ, OF BOSTON, MASSACHUSETTS.

HAMMOCK.

1,308,096.

Specification of Letters Patent.

Patented July 1, 1919.

Application filed March 26, 1919. Serial No. 285,243.

To all whom it may concern:

Be it known that I, HARRY MINTZ, a citizen of the United States, and resident of Boston, in the county of Suffolk and State 5 of Massachusetts, have invented new and useful Improvements in Hammocks, of which the following is a specification.

This invention relates to hammocks and more particularly to that type commonly known as couch or Gloucester hammocks which, according to the usual construction, comprise essentially a cushioned frame or seat with flexible end suspension members and a wind shield or back extending between 15 said end members.

The hammocks of this type heretofore provided with which I am familiar, contain no effective provision for adjusting the position of the back to the comfort of the user 20 under many of the conditions of use. Sometimes the user desires to sit upright against a straight or substantially straight back, while at others he desires to recline against the back, and adjustment of the angular relationship of the back to the seat in this essential particular is not possible where, as 25 is commonly the case, the back is laced or otherwise secured to the end members or is adjustable only in a vertical plane.

Again under many of the commonest conditions of use of this class of hammocks, as for example where the hammock is suspended from a veranda roof or from a stand upon a lawn, terrace or the like, users often 35 wish to seat themselves so as to face in one direction at one time and in the opposite direction at another time so as to insure privacy or for protection against the sun, or for other reasons. If, as is commonly the 40 case, the back is laced or otherwise secured to the end members, users must always face in a single direction and consequently it is a common practice, altogether to dispense with a back or wind shield, thus adapting 45 the hammock to the use stated but seriously interfering with the ease and comfort of the user.

It is the principal object of this invention to provide a hammock wherein the back 50 may be disposed at will along either side of the seat and tilted or inclined at various angles to insure the comfort of the user.

Referring to the drawings which illustrate an embodiment of the invention—

55 Figure 1 is an end view of a hammock

embodying my invention, the end suspension member being partly broken away;

Fig. 2 is a section on the line 2—2, Fig. 1, the cushion being removed;

Fig. 3 is a section on the line 3—3, Fig. 2; 60 Figs. 4 and 5 are end views of the hammock the end suspension member being removed.

A is an angle iron frame or seat of usual construction comprising end rails and side rails with spring fabric stretched therebetween. To said end rails are secured the usual flexible end members B provided with chains or the like for suspending the hammock from any suitable support such as the 70 ring C. The usual seat cushion or mattress D rests upon the seat or frame A.

E is the back consisting of a rectangular angle iron frame having end rails e and side rails with spring fabric stretched therebetween and provided with cushions e' on both 75 sides thereon.

Rigidly secured to each end rail of the frame A and at approximately the center thereof, is a lug F preferably hinged as 80 shown (Fig. 3) to permit it to be folded down upon the rail to protect it against the likelihood of injury when the hammock is packed for shipment. Links G are pivotally secured to said lugs F, and links H are 85 pivoted to the end rails e of the back frame, the free ends of said links G and H being pivotally secured at I, to form an articulated connection between the back and seat. Flexible supporting members such as the chains 90 J are secured at one end to the end rails e of the back E and are adapted to be secured at their other ends to the hammock supporting means.

It will be obvious that when a user desires 95 to move the back E from the position shown in full lines in Figs. 1 and 4 to the opposite side of the hammock, it is necessary merely to grasp the back and swing it upon its pivotal connection with the seat frame into the 100 dotted line position shown in Fig. 4. It will be equally obvious that by swinging the back upon the pivots I, the angular relationship of said back to the seat can be adjusted as shown in Fig. 5 to the position which the 105 user desires and which will best insure his comfort.

The means provided for effecting the advantages above described are very simple and strong and can easily be assembled by 110

persons without special mechanical skill or training, or without the employment of special tools, and there is nothing to detract from the artistic appearance of the hammock or to render it clumsy or unsightly. In short a hammock made in accordance with my invention as above described not only retains all the advantages of the hammocks of the usual construction but is provided in addition with means eliminating well known objections inherent in the prior construction and adapting it for uses under all usual conditions of service.

I claim:

1. A hammock comprising a seat having end rails, a lug fast on each end rail at approximately the center thereof, a back, pivotal connections between said lugs and back and flexible supporting means secured at one end to said back and at their opposite ends to the hammock supporting means in a vertical plane passing through said lugs, whereby said back can be disposed and supported along either side of said seat.

2. A hammock comprising a seat having end rails, a lug fast on each end rail at approximately the center thereof, links pivoted on said lugs, a back having end rails, links pivoted at one end to said end rails and at their opposite ends to said first named links, whereby said back can be disposed along either side of said seat and adjusted in angular relationship thereto.

3. A hammock comprising a seat having end rails, a lug fast on each end rail at approximately the center thereof, links pivoted on said lugs, a back having end rails, links pivoted at one end to said end rails, and at their opposite ends to said first named links, whereby said back can be disposed along either side of said seat and adjusted in angular relationship thereto, and flexible supporting means secured to said back and adapted to be secured to the hammock supporting means.

Signed at Boston, Massachusetts, this 25th day of March, 1919.

HARRY MINTZ.
